UNITED STATES PATENT OFFICE.

JAMES A. STORM, OF CHICAGO, ILLINOIS, ASSIGNOR TO THE STORM COMPANY, OF CHICAGO, ILLINOIS.

TICKET-DISPENSER.

1,239,981.

Specification of Letters Patent. Patented Sept. 11, 1917.

Application filed August 5, 1915. Serial No. 43,735.

To all whom it may concern:

Be it known, that I, JAMES A. STORM, a citizen of the United States, residing at Chicago, in the county of Cook and State of Illinois, have invented certain new and useful Improvements in Ticket-Dispensers, of which the following is a specification.

The invention relates to devices for serving or dispensing tickets, checks, receipts, etc., which are in strip form, and, in some of its features, is concerned more particularly with means for guiding, interrupting and severing so much of the ticket strip as may be desired.

Objects of the invention are to provide a simple and substantial holder for ticket rolls capable of being readily constructed from blanks of material cut properly to shape; to provide means for periodically halting or interrupting the movement of the ticket strip to apprise the operator of the position of the strip with reference to severing of tickets therefrom; to provide guides for the ticket strip such that bending, buckling or tearing of the material is prevented during movement thereof; and generally to so arrange, construct, and assemble the constituent parts of the device as to render expeditious, dependable and accurate the dispensing of tickets from the roll. These and other objects of the invention will in part be obvious, and will in part be set forth hereinafter.

In the accompanying drawings referred to herein, and forming a part hereof, and which illustrate one embodiment of the invention:—

Figure 1 is a side elevation of a device constructed in accordance with the principles of my invention, showing a roll of tickets mounted in operative position; Fig. 2 is a plan view of the device illustrated in Fig. 1; Fig. 3 is a detail in cross section of the delivery end of the device; Fig. 4 is a cross section taken on line 4—4 of Fig. 2; Fig. 5 is a cross section on line 5—5 of Fig. 2; Fig. 6 is a plan view of two devices, such as illustrated in Figs. 1 and 2, placed closely together, and illustrating the manner in which the ticket roll may be mounted in staggered relation to enable the devices to lie one against the other; Fig. 7 is a view of the blank from which the ticket roll holder is

constructed; Fig. 8 is a view of the blank from which the ticket guiding and severing means are formed; Fig. 9 is a view of the blank from which the ticket friction button is constructed; and Fig. 10 is a fragmentary plan view of two devices placed side by side, without interference with each other. 55 60

The present ticket dispenser may be formed conveniently of three elements, as shown in the drawing, so constructed, however, as to assume permanent relative position when mounted upon a base or block. 65 These three elements may be termed the roll holder 10^a, the ticket guide 11, and the friction button 12. A base or block 13 is also provided upon which the elements 10^a, 11, and 12 are mounted, the ticket guide alone, 70 however, when secured to the block, serving to retain the members 10^a and 12 in permanent position thereupon.

In Fig. 7 is exhibited the blank from which the roll holder 10^a is formed, comprising a base or connecting portion 14, from which extend sides 15 slotted as at 16. It is intended that these sides should be bent up in parallel relation, as shown in Figs. 1 and 2, to retain between them a ticket roll 80 17. Through a pair of alined slots 16, the ends of a pin or rod 18 may be extended such a pin or rod being passed axially through the ticket roll to thereby lock the same within the holder 10^a. 85

In many instances, it is desirable to locate two or more ticket rolls in adjoining positions, as shown in Fig. 6, in which case one of the axial rods 18 is extended through a pair of slots 16, while the rod 18, passing axially through the adjacent roll, is extended through another pair of slots in such a manner that the positions of the rolls are staggered or alternated with respect to each other. Such an arrangement permits the 95 ends of the rods or pins to protrude a considerable distance beyond the side walls of the roll holder without interference with the adjacent ticket roll or roll holder.

The manner in which two or more dispensers may be placed side by side in operative position to occupy the minimum space is illustrated in Figs. 6 and 10. In the former of these figures, the devices are shown in proximity to each other, while in 105 Fig. 10, the dispensers are arranged side by

side with no intervening space whatever therebetween, the protruding ends of the axial rods being staggered to not interfere with each other.

5 In Fig. 8 is shown the blank from which the guide member is constructed, being generally oblong in form with a tongue 19 at one end, a second tongue 20 at the other end, an opening 21 in the tongue 20, a tine 22 of 10 the same shape and size as the opening 21, the space from which said tine is struck being registered with the opening 21 when the tongue 20 is bent in operative position, a transverse slot 23 between the opening 21 15 and the tine 22, and a number of other elongated tines 24 extending longitudinally of the blank. When bent into serviceable form, the tongue 19 and tine 22 are extended at substantially right angles to the blank, 20 being capable of overlying the edges of the base or block 13. Fastening means, such as a nail or screw, may be driven through the tongue 19 and tine 22 to secure the ticket guide in place.

25 The tines 24 are each bent up at right angles to the blank to form guides for the ticket strip, the lines of bend being dotted. In like manner, the outer elongated edge portions 25 of the blank are bent perpendicularly to form outside walls upon the ticket guide. The tongue 20 is bent up and back upon the blank through substantially 180 degrees, its extreme end being curved upwardly, as shown in Fig. 3. When so 30 bent, the transverse slot 23 constitutes the delivery end of the device, the ticket strip issuing therethrough. As previously explained, the opening 21 will register with the space from which the tine 22 is struck 35 when the tongue is bent to position in the manner described. The purpose of these double registering openings, between which the ticket strip is passed, is to enable the operator to engage with his fingers the strip 40 from above and below to feed the same along.

The friction button 12, which remains to be considered, is shown in blank form in Fig. 9. This comprises a central tongue 26, 50 formed by slits extending inwardly from one side thereof, this construction resulting also in the formation of outer tongues 27. Two or more depressions or friction buttons 28 are provided as shown, these being intended 55 to lie in the path of the strip edge which is commonly notched at intervals.

The three elements 10^a, 11 and 12, whose construction has been described in detail, 60 are designed to lock together in operative relation, when mounted upon a suitable block or base, such as that illustrated and described. In assembling, the sides 15 of the ticket holder 10^a are passed upwardly through two of the spaces in the ticket guide 65 which result from the bending to position

of the tines 24. The outside walls 25, as well as the unbroken portions of material connecting the central and outer portions of the ticket guide, serve to determine accurately the assembled position of the ticket holder. 70 The friction button is likewise fastened in position upon the guide, its outside tongues 27 being passed through the ends of two of the spaces in the ticket guide resulting from the bending to position of the tines 24, after 75 which the tongues are bent flat against the underside of the guide. The ticket button, when thus positioned, is securely fastened in place. To facilitate passage of the ticket strip beneath the central tongue 26, 80 its free edge is curved upwardly, as appears best in Fig. 3. The three elements 10^a, 11 and 12 are operatively and permanently locked together, when the ticket guide is secured to the base or block 13, as previously 85 explained.

In use, a roll of ticket strip is placed within the holder, the ends of the axial rod 18 lying within two of the slots 16. The roll which rests upon the surface of the 90 guide member unwinds the strip in the direction of the delivery end of the guide, which, as I have stated, terminates in the transverse slot 23. The strip passes along the surface of the guide, between and adjacent the bent up tines 24 which determine its course, beneath the friction button 12 which engages the edge portions of the strip, beneath the bent back tongue 20, and emerges out through the slot 23. The advancement of the strip is marked by periodic hesitations or halts, due to successive engagement of the buttons 28 within the notches in the strip edge. In order to insure this hesitation or halting action, and thereby apprise the operator of the number of tickets or amount of strip being advanced, it is contemplated that the friction button should be formed of such a material, or be so mounted as to exert the proper retarding 100 effect. The buttons 28 are located with respect to the delivery end of the device, a distance which is coincident with the length of one or more tickets on the strip, so that, 105 when the buttons are engaged within a pair of notches in the strip edge, another pair of notches will lie immediately adjacent the delivery end of the device. The severing of so much of the strip as is desired is accomplished by laterally drawing the emerged 110 portion of the strip, which causes the material to be torn in a straight line across the delivery end of the device. In this manner, the desired number of tickets may be severed from the strip. Manifestly, as will be 115 seen by reference to Figs. 2, 3 and 4, the ticket strip is held to movement in a straight line by the tines 24, and bending, buckling or tearing of the strip within the device is likewise prevented by the support afforded 120 130

to the strip in its advancement over a smooth continuous surface and beneath the friction button and tongue 20.

The rearward edges of the tongue 20 and 5 of the friction button 12, as appears best from Fig. 3 of the drawing, are inclined upwardly in such a way as to present the least obstruction and friction to the movement of the strip, the places where the friction button and tongue approach closest to the surface of the guide constituting, in effect, a closed chute through which the strip emerges. The advantage of this construction is especially apparent when a new 10 roll of strip must be projected through the guide to replace another roll just used up. At such times, the tendency is greatest for the strip to buckle or bend up within the guide, thereby clogging its passage. Furthermore, the delivery end of the guide 15 which is formed by turning back the tongue 20, presents at its extremity two edges, one above and the other below the strip, either of which serves as a cutting edge over which 20 the strip may be torn off. It will be observed, moreover, that a substantially unbroken surface extends from end to end of the guide, the walls 24 serving to direct movement of the ticket strip in a straight 25 line, and the reinforcing walls 25 imparting the necessary longitudinal strength to the structure over its entire length.

The device herein shown and described may conveniently be formed from sheet 30 metal, the blanks being readily cut to shape as by the use of appropriate dies. When assembled for purposes of operation, it is manifest that no nuts, bolts, screws, rivets or parts of any kind are required, the elements being held firmly together when the 35 guide is fastened or screwed to a suitable base or block. Obviously, such a construction of ticket dispenser presents a minimum of parts, is practically fool-proof, and eliminates as far as possible all likelihood of 40 trouble or breakage which commonly arises from a multiplicity of parts or complicated mechanism.

I claim:

50 1. A ticket dispenser, including in combination, a guide of sheet metal bent to provide sides for a portion of its length to constitute in effect a U-shaped member within which a notch edged ticket strip is guided in 55 a straight course of travel, the guide near its delivery end being formed with two complementary relatively longitudinal openings and with a relatively transverse slot situated therebetween, and having the extremity of 60 the delivery end thereof bent back upon itself upon a line intersecting the transverse slot to constitute a fourth side to the guide at its delivery end, with the relatively longitudinal openings therein brought into register, substantially as described.

2. A dispenser for ticket strips, including, in combination, a guide for the strip formed of a single piece of sheet material provided with a transverse slot near the delivery end thereof, the delivery end of the guide being 70 bent back upon itself upon a line intersecting the transverse slot whereby the edges of the slot constitute the extremity of the guide from which the strip is issued, and over either of which the strip may be torn off, 75 substantially as described.

3. A dispenser for ticket strips, including, in combination, a guide for the strip formed of a single piece of sheet material provided with two complementary openings situated 80 longitudinally of each other near the delivery end of the guide, and provided further with a transverse slot intermediate said complementary openings, the delivery end of the guide being bent back upon itself upon 85 a line intersecting the transverse slot to bring the two complementary openings into register, whereby the strip of ticket extending beneath the bent back portion of the guide and out through the transverse slot 90 may be fed along by pressure of the fingers applied upon opposite sides of the strip through said openings, substantially as described.

4. A dispenser for notch edged ticket 95 strips, including, in combination, a guide for the strip formed of a single piece of sheet material having portions thereof bent up to provide lateral supports for the strip, and having a transverse slot near the delivery 100 end thereof, the delivery end of the guide being bent back upon itself upon a line intersecting the transverse slot whereby the edges of the slot constitute the extremity of the guide from which the strip is issued, 105 and over either edge of which the strip may be torn off, and a friction button positioned upon the guide a distance of one or more ticket lengths from the delivery end thereof arranged to engage successively within the 110 notches of the strip, whereby movement of the strip is periodically halted at intervals coincident with advancement of ticket notches to a point adjacent the delivery end of the guide, substantially as described. 115

5. A dispenser for notch edged ticket strips, including, in combination, a guide for the strip formed of a single piece of sheet material bent up to provide lateral supports for the strip, and a friction element upon 120 the guide comprising a tension element arranged to engage successively within the notches of the strip, and tongues struck from the friction element arranged to lock through portions of the guide not traversed 125 by the strip, whereby the friction element is permanently secured in position upon the guide, substantially as described.

6. A dispenser for rolls of notch edged ticket strips, including, in combination, a 130

guide for the strip formed of a single piece of sheet material having elongated tines struck out from the body thereof to form lateral supports for the strip, a U-shaped holder for the strip having its arms extended in opposite sides of the guide through openings resulting from the formation of the tines, the arms of the holder and openings

being shaped to coöperate to fixedly establish the position of the holder with respect to the guide, substantially as described.

JAMES A. STORM.
